UNITED STATES PATENT OFFICE.

ROY A. WEAGANT, OF NEW YORK, N. Y., ASSIGNOR TO RADIO CORPORATION OF AMERICA, A CORPORATION OF DELAWARE.

WIRELESS-TELEGRAPH RECEIVING APPARATUS.

Application filed April 14, 1920, Serial No. 373,929. Renewed April 1, 1927.

It is well known in the art of wireless telegraphy that transmission by continuous waves is preferable to transmission by damped waves. It is also known that the nearer the continuous wave approaches a sine wave the better it will carry, especially in long distance transmission. For this reason "wireless" or "radio" signals should be propagated to the point of reception without alteration of the sinusoidal character. The frequencies of the propagated waves in practical use, however, are much too high to operate the diaphragm of a telephone receiver and even if this could be done the pitch would be too high to be audible to the human ear. In view of this it is necessary to so alter or "modulate" the continuous wave at the point of reception, that the telephone receiver will produce an audible note, or in some other way render the signal perceptible. This enables the operator to clearly hear or otherwise perceive the dots and dashes, for instance, of the message that has travelled throughout the entire distance in the form of sine waves, except for what modification may have been produced by the medium through which the waves are propagated.

There are known methods of modulation of continuous waves for reception purposes but I have devised further means and methods of accomplishing the desired results and in an entirely novel manner, as far as I am aware.

It can be shown both mathematically and experimentally that if two frequencies n and n' be applied to the in-put side of an electron relay such as a three element vacuum tube, for instance, so as to cause a flow of current in the in-put circuit, there can be developed in the out-put or plate circuit of the valve a current having components of frequencies $n+n'$ and $n-n'$. If this plate current in turn be applied to the in-put side of a similar valve the out-put current will have components with frequency $(n+n') - (n-n')$ and $(n+n') - (n-n')$, or $2n$ and $2n'$ respectively. It is in accordance with this phenomena that I produced the novel results referred to.

Briefly, my invention consists in receiving the incoming continuous signal of some frequency in the in-put circuit of the valve or equivalent and superimposing an E. M. F. of frequency n' in this same circuit, which

is either an audible frequency or an inaudible frequency modulated to secure the results desired. These two frequencies then result in the other frequencies in the plate circuit as already described. Since the local frequency is an audible one, or is a modulated high frequency, at least one of the plate current frequencies will be audible in the receiving device. With this general description of my invention specific embodiments will now be described to render clear the manner in which the improvement may be carried out.

Referring to the drawings:

Fig. 1 is a circuit diagram for the reception of waves in accordance with my invention.

Fig. 2 is a modification.

Fig. 3 is a further modification of the embodiment shown in Fig. 2.

Fig. 4 is an additional modification.

In Fig. 1 of the drawings a grounded antenna shown conventionally at 1 contains a variable capacity 2 and the primary 3 of a transformer. One terminal of the secondary 4 of this transformer is connected to a grid 5 of a three element valve (shown diagrammatically) and the other to the filament 6 which is heated by some local source such as a battery 7. A condenser 9 may also be placed in the lead connected to the grid 5. The connection to the filament 6 includes means for superimposing a local E. M. F. in the in-put circuit such as a secondary 8 of a transformer, the primary of which is connected to a generator 10 or other source of alternating current having an audible frequency 500 for example.

The grid should, for best working, be kept negative and this may be accomplished by putting the condenser 9 in the circuit with a grid leak 9' therearound. The same result could be accomplished by putting a battery in this circuit with the negative terminal connected to the grid as shown in Fig. 2 at 10'.

The plate 11 is joined to the filament 6 through the battery 12 and primary 13 of a transformer whose secondary 14 is connected to the grid 15 and filament 16 of a second three element valve. The plate 17 of this valve is joined to the filament 16 through the battery 18 and telephone receiver 19 or the like.

In both of the valves described above, the variable capacities 20 and 21 are connected

across the transformer primaries in well known ways.

The operation of the embodiment shown in Fig. 1 is as follows:

5 The incoming signal induces an E. M. F. of frequency n in the antenna which frequency may be too high to be audible in a receiving circuit. An E. M. F. of frequency n is induced in the secondary 4 and on this 10 is superimposed a local E. M. F. of audible frequency n' by means of the local source described. The current produced by these 15 combined E. M. F's in the plate circuit of the first valve has components $(n+n')$ and $(n-n')$. The transformer 13, 14 introduces an E. M. F. in the in-put circuit of the second valve that causes a flow of current having two components $(n+n')+(n-n')$ and 20 $(n+n')-(n-n')$. By simplification the two frequencies reduce to $2n$ and $2n'$.

By way of example, the incoming signal of frequency n will be considered to have the value 25000 and the local frequency n' , a value of 500. The in-put circuit of a second 25 valve is "tuned" to substantially the frequency of the incoming signal, that is, in the neighborhood of 25000 cycles, and with this adjustment the local frequency of 500 will not get into the in-put circuit of the 30 second valve when the signal is not coming in. Hence the local frequency will be inaudible in the receiving device 19. When the signal comes in, the current of the plate circuit of the first valve, having the 35 two components will get across into the in-put circuit of the second valve as it will be of the order of the frequency to which the system is adjusted or tuned. The two components referred to will have the 40 frequency 25500, that is, $(n+n')$ and 24500, that is, $(n-n')$ and current in the plate circuit of the first valve will induce a current of similar components in the in-put circuit of the second valve. This in turn will 45 produce a current in the out-put circuit of the second valve containing the receiver 19, having components of the frequency 50000 $(2n)$ and 1000 $(2n')$. A 50000 frequency cannot produce an audible tone in the receiver 19 whereas the 1000 frequency can do this. Hence, the latter is heard by the operator. Since no current of audible frequency is induced in the secondary 14 when the signal is not coming in, that is, during the period of time between the dots and dashes, for instance, the receiver diaphragm will not be set in vibration. The dots and dashes therefore will alone produce vibration of the receiver diaphragm at a frequency of 1000 and the signals will be plainly heard by the operator.

In the modification in Fig. 2 the local source of frequency is not a low frequency as in Fig. 1 but is a high frequency on which is superimposed a low frequency. In

this figure as well as in the remaining figures the parts shown in Fig. 1 are given similar reference characters and a detailed description need not be repeated. The local source of frequency may consist of any desired device but I have illustrated by way of example an oscillating valve well known in the art. The plate circuit 22 of this valve is connected to the in-put circuit of the first receiving valve by means of a primary 23 of a transformer. A local source of E. M. F. 24 induces a current by means of a transformer 25 in the grid circuit of the oscillating valve. A mathematical treatise of this embodiment wherein all of the frequencies 70 are taken into account would be too involved for this disclosure, and therefore, a consideration of the frequency of the incoming signal and the local high frequency will be the only ones that will be essential. The low frequency n' of the local source 24 will be considered to alter or modulate the local high frequency n'' so wherever the latter, or combinations of the latter with incoming signal is involved, it must be considered that the resulting components are modulated by the local low frequency n' .

With this understanding, the operation 75 may now be explained. By way of example, the frequency n of the incoming signal will be considered to have the value of 25000, the local high frequency n'' a value of 50,000 and the local low frequency n' a value of 500. The incoming signal, as before, generates an E. M. F. in the secondary 4 in 80 which is generated a local E. M. F. having a frequency of 50000 (modulated or altered by the low frequency 500). Since the incoming signal generates an E. M. F. of 25000 cycles in this same circuit there will be produced in the plate circuit of the first valve a current having components with frequencies equal to the sums and differences of the said frequencies. This will mean that the two components referred to have frequencies of 100 $(n+n'')$, and 25000 $(n''-n)$, both of 105 which are modulated or changed by the local frequency 500.

The in-put circuit of the second valve is 110 tuned for the frequency of 25000 or in this neighborhood. This adjustment, therefore, will not permit passage of the component having the frequency of 75000, but will pass the frequency of 25000 which, of course, is modulated. The 25000 cycles current will not in itself operate the diaphragm of receiver 19 as it is entirely too high, but the modulation of this frequency, by the low frequency 500, will produce an audible note in the receiver, and this has been intensified by the local high frequency.

One distinct advantage of the system in Fig. 2 over that of Fig. 1 is the amplification due to the combination of the local high frequency of 50000 with the incoming signal 120

of 25000. By referring to the previous paragraph it will be seen that one of the frequencies of 25000 that passed into the input circuit of the second valve is due to the difference between the signal n and the local high frequency n'' . This is the combination that gives marked amplification of the signal. This frequency of 25000 is the one that is modulated by the local 500 frequency to render it audible.

In Fig. 3 I have shown a modification of the arrangement of Fig. 2 wherein the battery of the plate circuit is displaced by a source of variable electro motive force such as an alternating generator 26. By making the frequency of this generator of low value, say 500, for example, the local source 24 may be dispensed with. In other words, the source 26 of Fig. 3 takes the place of both the battery in the plate circuit and the generator 24 of Fig. 2. Obviously various forms of generators may be used in place of the alternator. The operation of this modification would be the same as the system in Fig. 2.

Referring to Fig. 4 the secondary 8 of the transformer in the in-put circuit of the first valve has induced in it two electro motive forces of high frequencies due to the transformers 23' and 23'' in two oscillating valve circuits as clearly shown. One of these oscillating valves is adjusted to generate an E. M. F. of high frequency, say 50000, and the other one a slightly different frequency, say 50500. Thus, there will be produced in the in-put circuit of the first valve a frequency of 50000 and a frequency of 50500. The in-put circuit of the second valve may be tuned to pass 25000 cycles, or a frequency in this neighborhood. This will cut out all but the frequencies 25500 and 25000, both of which are combinations of the incoming signal with the local high frequency, consequently amplification may be made very great due to the amount of energy that can be put into the system by the local source. The out-put circuit of the second valve will have a current with components of the sum and difference of the frequencies of the in-put circuit, namely, $25500+25000$ or 50500 and $25500-25000$ or 500. The telephone receiver 19 will therefore vibrate at a frequency of 500 which will produce an audible note.

In the operation of the systems I have observed that the arrangement of Fig. 3 is most sensitive, that of Fig. 2 the next sensitive, and that of Fig. 1 the least sensitive when the incoming signal is weak. When, however, the incoming signals are moderate or of great intensity the systems in Fig. 1 and Fig. 2 have about equal sensitiveness and produce greater movement of the diaphragm than is the case with the systems

of Fig. 3. However, I do not wish to state that this will always be the case, as under some circumstances it might be different.

I find that if the frequency of the local source is exactly twice that of the incoming signal the operation is especially satisfactory and the adjustments very simple, since in this case the in-put circuits of both valves are then tuned to the signal frequencies, one of the new frequencies will be equal to the signal frequency.

I also find by actual test that the systems of Figs. 2 and 4, under most conditions, especially the latter, give excellent response, are exceedingly sensitive, and show great capability of working through interference and of increasing the ratio of signal strength to static strength.

While I have chosen certain frequencies to explain the operation of the various systems, it will be understood that these have been by way of example only and that various other frequencies of signal and local source of energy may be used with like results when the adjustments are made in accordance with my explanation or equivalent thereto.

It will be apparent that various forms of generators may be used in the place of those that I have described without departing from the spirit of invention. Receiving devices other than the three element tube may also be used. As one example, I may cite the crystal detector, but I prefer the oscillating tubes on account of the ease of adjustment and the superior results obtained.

While I believe the theory of operation to be correct I am not bound by it. I do know that the arrangement produces the results desired.

Having described my invention, what I claim is:

1. The method of receiving radio signals which consists in generating in a circuit an electro motive force of the signal frequency, generating in said circuit two local electro motive forces of frequencies differing widely from the signal frequencies and differing from each other by an audible frequency and causing a component of the current resulting from said electro motive forces to operate a receiving device.

2. The method of receiving radio signals which consists in generating in a circuit an electro motive force of the signal frequency, generating in said circuit two local electro motive forces of frequencies differing widely from the signal frequency and differing from each other by an audible frequency producing by said electro motive forces a current having a plurality of components, of frequencies that are integral combinations of the frequencies of said electro motive forces, producing in a second circuit a current

equivalent to at least one of said components and operating a receiving device by said component.

3. The method of receiving signals which consists in generating a signal electromotive force, generating a second and a third electromotive force differing from each other by a low frequency and from the signal frequency by a high frequency, combining all said electromotive forces to create a first and a second component having frequencies respectively equal to the difference between the frequency of the signal and that of each of the other said electromotive forces, combining said first and second components to produce a third component having a frequency equal to the difference between the frequencies of said first and second components, the frequency of the third component also being equal to the difference between the frequencies of said second and third electromotive force and independent of the frequency of the signal, and indicating the signal by said third component.

4. The method of receiving signals which consists in generating a signal electromotive force, generating a second and a third electromotive force differing from each other by a low frequency and from the signal frequency by a high frequency, combining all

30 said electromotive forces to create a first and

a second component having frequencies respectively equal to the difference between the frequency of the signal and that of each of the other said electromotive forces, combining said first and second components to produce a third component having a frequency equal to the difference between the frequencies of said first and second components, the frequency of the third component also being equal to the difference between the frequencies of said second and third electromotive force and independent of the frequency of the signal, and indicating the signal by said third component.

5. A receiving apparatus comprising in combination an electronic relay having an input circuit and an output circuit, means whereby signaling oscillations are brought into said input circuit, local means for producing in said input circuit an electromotive force of a relatively high frequency as compared to that of the signaling oscillations, a second local means connected to said input circuit and producing an electromotive force interacting therein with that produced by said first local means, and means connected to said output circuit for indicating the signals.

R. A. WEAGANT.
